UNITED STATES PATENT OFFICE

168,489

AUTOMOBILE SIGN OR THE LIKE

Paul H. Wasmund, Elmhurst, N. Y.

Application April 15, 1952, Serial No. 19,320

Term of patent 14 years

(Cl. D29—2)

To all whom it may concern:

Be it known, that I, Paul H. Wasmund, a citizen of the United States, residing in Elmhurst, in the county of Queens and State of New York, have invented a new, original, and ornamental Design for an Automobile Sign or the like, of which the following is a specification, reference being had to the accompanying drawing, forming part thereof.

Fig. 1 is a front perspective view of an automobile sign or the like, showing my new design; and

Fig. 2 is a rear perspective view thereof.

I claim:

The ornamental design for an automobile sign or the like, substantially as shown.

PAUL H. WASMUND.
